UNITED STATES PATENT OFFICE

170,877

LUMINAIRE

Robert W. Loehr, Lakewood, Ohio, assignor to
Westinghouse Electric Corporation, a corpora-
tion of Pennsylvania

Application December 31, 1952, Serial No. 22,959

Term of patent 14 years

(Cl. D48—31)

To all whom it may concern:

Be it known that I, Robert W. Loehr, a citizen of the United States, residing at Lakewood, in the county of Cuyahoga and State of Ohio, have invented a new, original, and ornamental Design for a Luminaire, of which the following is a specification, reference being had to the accompanying drawings forming a part thereof, in which:

Figure 1 is a top plan view of a luminaire, showing my new design.

Fig. 2 is a side elevational view thereof.

Fig. 3 is an end elevational view taken from the left of Fig. 2; and

Fig. 4 is an elevational view showing the end opposite Fig. 3.

The dominant features of my design are shown in the drawings by solid lines.

I claim:

The ornamental design for a luminaire, as shown and described.

ROBERT W. LOEHR.
